UNITED STATES PATENT OFFICE.

CLARENCE H. JONES, OF SEATTLE, WASHINGTON, ASSIGNOR OF ONE-HALF TO HENRY C. BROMLEY, OF SEATTLE, WASHINGTON.

CASING FOR PILES.

1,211,164.

Specification of Letters Patent.

Patented Jan. 2, 1917.

Application filed March 20, 1913. Serial No. 756,829.

To all whom it may concern:

Be it known that I, CLARENCE H. JONES, a citizen of the United States, and resident of the city of Seattle, in the county of King and State of Washington, have invented certain new and useful Improvements in Casings for Piles, of which the following is a specification.

My invention relates to an improvement in protective coverings for piles, and comprises the novel parts and combinations of parts which will be hereinafter described and particularly pointed out in the claims.

The object of my invention is to provide a plan and means whereby a covering or casing may be placed about a pile so as to protect it from the destructive work of the teredo and like insect enemies, and also to strengthen the same and make of the pile a permanent structure.

One of the important features of my invention, is the making of the covering or casing, in such way that it may be applied to a pile having a stringer or cap thereon, without necessitating the removal of said cap or stringer.

It is also a feature of my invention that the casing is composed of concrete or a like substance which is cheap to make, strong, and is as nearly indestructible as it is possible to use.

In the accompanying drawings I have shown my invention embodied in the form which is now preferred by me.

Figure 1 is an elevation of a casing made in accordance with my invention. Fig. 2 is a central sectional elevation of the same. Fig. 3 is a transverse section through the main portion or body of the casing. Fig. 4

is a plan view of the pile-centering rings which are placed at the lower end of the casing. Fig. 5 is a bottom plan view of the lowermost or base sections.

The central idea of my invention, is the use of a casing, molded of concrete, in sections, each section extending peripherally partly about the pile, ordinarily half way around, and in such length as may be conveniently handled, the segments being added to as necessary to get the desired length. These segments are provided with interlocking constructions on their edges and the ends of those segments in one vertical row are arranged to come at the middle part of those 55 of the adjacent row, so that all joints are

broken and the entire column of casing segments are locked together to form a strong tubular column surrounding the pile.

As a base, two special segments are used, having a broad footing 21, thereby providing an increased bearing surface for carrying the load. These base sections 2 and 20, are provided with a downwardly projecting lip, or flange, surrounding the pile-receiving opening. This lip, 23, is preferably tapering on its external surface and is designed to project into the mud and earth about the pile to prevent escape of the concrete, which is later filled into the space between casing and pile. I have also shown this lip as provided with ribs 24, extending vertically on its outer surface. When the pile casing has been assembled and lowered into contact with the bottom, by slight turning movement thereof, it may be made to sink into the bottom, the ribs 24 assisting in disturbing and loosening the earth and giving slightly easier penetration.

The segments, as herein shown, are all made to extend half way about the pile, although this proportion may be varied within certain limits. From the upper surface of the footings 21, extend the short sections of semi-tubular shape, which form the casing proper. The portion 26 which forms a part of the base section 2, is of greater length than the part 27 which forms a part of the base section 20. The difference between the lengths of these parts is, preferably, half the length of those segments which are used in making the main body of the casing. The purpose of this is to cause the transverse joints of the successive segments and opposite halves to break joints.

The segments which form the body of the casing above the base, consist of semi-tubular members 1, of a size to match with the semi-tubular portions 26 and 27 of the base segments. The vertical meeting edges of these segments, are molded to such a shape that they dovetail, or interlock, so as to prevent separation when once assembled. The assembling is done by sliding them together lengthwise, or in a direction parallel with their axis. The form of joint which I now prefer, is shown in the transverse section of Fig. 3, the dovetailed head 10, being on the inner side of one segment, and the complementary dovetailed head 11, being on the outer side of the companion segment. The por-

tion of the base segments 2 and 20, have like interlocking construction, extending downward to about the lower edge of the base footing and there stopping. From this point downward, the edges meet as flush faces. This forms a stop to prevent one side of the base slipping farther down than the other.

The meeting end edges of the segments 10 are hollowed at one end and pointed at the other, as shown in Fig. 2 at 3, whereby side displacement is further prevented. Any other equivalent shape which secures like results might be used. As one of the lower 15 or base sections is shorter than the other, so the upper end of the casing has one segment, 12, of half length, so that both sides will terminate evenly.

The opening within the casing should be 20 enough larger than the pile to permit free sliding of the casing thereon. It should also be enough larger to form a reasonable space for the reception of the cement or concrete which is poured therein.

25 The central opening within the lip 24, beneath the base footings 21, is made slightly larger than above that point, so as to leave a ledge 25, against which a ring 4 of wood, made in two parts, may be placed, the inner 30 circle of this wood ring being as close a fit about the pile as possible, without causing it to bind when lowering. The ring 40, beneath this is made to fit tightly within the recess, to thereby hold the other ring 35 surely in place. The purpose of these rings is to prevent mud from entering the space between the base segments and the pile.

In molding the base segments, reinforcing bars 22, may be employed. Each of the 40 segments should have some means for binding them to the inner lining layer of concrete. The means herein shown consist of bonding strips 5, of metal, which are molded in place in the casing segments.

45 The lower, or base, segments have recesses 28, in their outer surface, adapted to receive hooks, by which they may be supported while assembling the upper segments and during lowering. The casing is lowered as 50 it is built up from the top until it reaches and beds itself in the bottom. The ropes carrying the hooks by which it is supported, are then slackened off, being thereby released from the holes, and drawn up.

55 After the casing has been assembled and settled in place, thin concrete or grouting, is poured into the space between the casing and pile. This thoroughly bonds the sections of the casing together and to the pile, 60 making of the whole a substantially unitary structure, consisting of a wooden core or center and a concrete column surrounding and supporting the same. The cement entering between the joints of the casing segments binds them securely together. The

strength of the pile has been much increased, the concrete thereafter being relied upon as the chief supporting element. Such a covering placed about piles in locations where they are subject to the ravages of the teredo 70 and like worms, will protect them absolutely against further ravages. The segments being divided lengthwise so as to reach half way about the pile, may be placed upon piles which are in use and which have beams 75 thereon which would prevent slipping the piles on lengthwise. This covering may be placed upon piles which have been somewhat acted upon by the teredos, with the result that the teredos which are then within 80 the pile will be killed, as they cannot get any further supply of salt water, and no more can obtain access to the wooden core. The concrete will strengthen the pile so that it becomes as strong to carry weight as it 85 originally was.

The sections herein described as forming the body of the casing above the base, may be employed to advantage in any place and for any purpose where a casing or a tubular 90 conduit may be required, whether this conduit be placed in a vertical or in a horizontal position. Sections such as sections 1, may be made wherever convenient and assembled to serve, for instance, as a sewer, 95 or for other like purposes. When used in this way cement may, or should, be placed in the joints between the sections, both for the purpose of more securely joining them together and to make the joints tight against 100 leakage. To assemble the sections and to place the cement in the joints is a simple and rapid operation. The completed conduit will then be cemented together to closely 105 resemble a monolithic structure in its characteristics.

What I claim as my invention is:

1. A casing for piles comprising a base section composed of two segments, each having an outwardly extending footing, a downwardly extending lip or flange bordering the central pile-receiving opening, and an upwardly extending semi-tubular shell, said segments having meeting edges provided with complementary interlocking constructions adapted to be engaged by relative axial movements.

2. A casing for piles having a base section composed of two segments divided along vertical lines, their meeting edges having complementary interlocking shapes adapted to be engaged by lengthwise movement, each segment having outwardly extending footings and a downwardly extending lip or flange bordering the pile-receiving opening 110 and an upwardly extending semi-tubular shell, which shells are of unequal length 115 for the respective segments.

3. A pile comprising a continuous central wooden core and a protective casing 120

therefor composed of segmental concrete sections having their vertical edges of complementary interlocking shape integral therewith and engageable by relative axial movements.

4. A pile comprising a continuous central wooden core and a protective casing therefor composed of segmental concrete sections having their vertical edges of complementary 10 interlocking shape integral therewith and engageable by relative axial movements, said sections also having interlocking end shapes.

5. A pile comprising a continuous central wooden core and a protective casing 15 therefor composed of segmental concrete sections having their vertical edges of com-

plementary interlocking shape integral therewith and engageable by relative axial movements, said concrete segments being of a size to be spaced outward from the central 20 wooden core when in place and a filling for the space between core and inclosing segments composed of cementitious material placed therein when in a plastic state.

In testimony whereof I have hereunto affixed my signature at Seattle, Washington, this 14 day of March, 1913.

CLARENCE H. JONES.
